PROTECTIVE SHIELD FOR SEWING
MACHINESCharles F. Rubel, Chicago, Ill., assignor to Union
Special Machine Company, Chicago, Ill., a cor-
poration of Illinois

Application December 27, 1940, Serial No. 371,895

8 Claims. (Cl. 112—261)

This invention relates to shields for sewing machines, that is to say, to shields designed to prevent discomfort or injury to the operators who run the machines.

In operating certain types of sewing machines, particularly those of the feed off the arm variety, the arm of the operator is rested on the work support while manipulating the fabric which is being sewed. As a consequence of frictional heat generated incident to high speed rotation of actuating mechanism within the work support, and the conduction of such heat (which in some instances rises to 125° F. or more) to the top surface of the work support wherein the operator's arm rests, considerable discomfort or even injury is likely to ensue.

The chief aim of my invention is to overcome the above contingency, which objective I make possible of realization in practice, as hereinafter more fully disclosed, through provision of a shield which constitutes an auxiliary arm rest and which is sustained with provision of an interval between it and the work support of the sewing machine to prevent conduction thereto of frictional heat from the mechanism within said arm.

Other objects and attendant advantages will appear from the following detailed description of the attached drawings, wherein Fig. 1 shows the front elevation of a feed off the arm sewing machine conveniently embodying the protective shield of my invention.

Fig. 2 shows the machine in top plan.

Figs. 3, 4 and 5 are detail sectional views taken as respectively indicated by the angled arrows III—III, IV—IV and V—V in Fig. 2.

Fig. 6 is a perspective view of the removable top cover plate for the work support of the machine; and

Fig. 7 is a perspective view of the protective shield of my invention.

Fig. 8 is a detail sectional view taken as indicated by the angled arrows VIII—VIII in Fig. 7.

The sewing machine which I have illustrated for convenience of exemplifying my invention is generally of the construction featured in a co-pending patent application Serial No. 306,826, filed by Norman V. Christensen on November 30, 1939. As shown, the frame of the machine has a flat base 10 from which extends horizontally and at an angle, the anchorage portion 11a of a hollow work supporting arm 11 whereof the free end portion 11b is substantially at right angles to said anchorage portion. Rising from the base 10 is a hollow standard 12 from the top of which extends a horizontal arm 13 whereof the front end over-

reaches the free end portion of the work arm 11. Confined to up and down movement in the outer end of the arm 13 is a vertical axis needle bar 14, which, through suitable means not illustrated, is actuated from a rotary shaft 15 within said arm, and which, at its lower end, carries a pair of needles 16. At its right hand end, the shaft 15 extends through a bearing boss 17 on the standard and on its protruding end carries a combined hand and belt wheel 18 whereby the machine may be operated either manually or under power. Co-operating with the needles 16 in stitch formation within the outer end of the portion 11b of the work arm are suitable loopers (not illustrated), which, together with suitable feed means (likewise not illustrated) also within said portion 11b, are actuated by mechanism 20 (Fig. 3) within the anchorage portion 11a of said work arm. As shown, the mechanism 20 includes a shaft 21 which is journaled in bearings 22, 23 and 24 at the interior of the work arm portion 11a, and which is rotated through a bevel gear pinion 25 by suitable drive mechanism (not illustrated) within the standard 12 connected to the needle actuating shaft 15. From Fig. 3, it will be observed that the shaft 21 extends through the bearing 22 at the elbow of the work arm 11 for attachment thereto of a rotary take-up 26 for the looper thread or threads used in the machine, said take-up being protected by a downwardly swingable hollow cover 27 hinged to said work arm. The machine is equipped with a folder 28, which, see Fig. 2, is secured to a slide 29 mounted with capacity for movement longitudinally of the free end portion 11b of the work arm 11. Accordingly when desired, the folder may be withdrawn from the region of stitch formation. For convenience of access to the mechanism at the interior of the work arm 11, the latter is fitted with a removable top cover plate 30 which conforms generally to the shape of said arm, and which is secured to the latter adjacent its edges, with interposition of an oil sealing gasket 31, by screws 32 and 33. In the use of sewing machines of the described type, the operator sits with the free end portion 11b of the work support 11 in a direct line before her and rests her right arm on the anchorage portion 11a of said work arm with her right hand positioned laterally adjacent the folder 28. Then with her left hand correspondingly positioned at the outer side of the free end portion 11b of the work arm 11, she manipulates the work with her two hands to guide its edges into the folder 28.

During high speed operation of the machine,

considerable heat is generated by friction of the shaft 21 within its bearings, which heat may reach a temperature of 125° F. or more, and which is transmitted directly to the cover plate 30 of the work arm 11 whereon the right hand arm of the operator rests, with resultant causation of considerable discomfort and in some instances pain and injury. With a view toward overcoming this difficulty, I have provided in accordance with my invention, a protective shield 35 which is separately illustrated in perspective in Fig. 6. As shown, this shield 35 is fashioned from sheet material, preferably metal, to the general configuration of the cover plate 30, which is separately illustrated in perspective in Fig. 7, and hence of the work arm 11. When in position on the machine the portion 35a of the shield 35 is supported with provision of an interspace between it and the corresponding portion 30a of the cover plate 30 upon a plurality (in this instance four) of suitably spaced lugs 36 of small area upstanding from said plate (Figs. 7 and 8) adjacent its edges, and secured by screws 37 (Fig. 2) whereof the shanks threadedly engage into said studs. The portion 35a of the shield is pierced as shown in Fig. 6 for convenience of access to the heads of the screws 32 by which the cover plate 30 is secured in position. The portion 35b of the shield 35 is bent downwardly as at 35c to contact directly with the corresponding end portion 30b of the cover plate 30, and bifurcated as at 35d to clear the slide 29 which carries the folder 28. The end portion 35b of the shield 35 is moreover also pierced as shown in Fig. 6 so that it may be secured by the same screws 33 which serve for the corresponding end 30b of the cover plate.

It will be further noted that the portion 35a of the shield 35 is provided with openings 38 and 39 in line with downwardly embossed openings 40 and 41 in the cover plate 30, for exposure of the upper ends of transparent sight gauge elements 42 and 43 through which the lubricating oil level in the compartments 44 and 45 of the work arm 11 may be observed. The shield 35 is swelled somewhat at 46 to clear an upward protrusion 47 of the cover plate 30, and, see Fig. 4, may carry on its bottom face a tension device 48 for the looper thread or threads. As shown in Fig. 7, the cover plate 30 has a cut out or notch 49 to clear the tension device 48 which, see Fig. 4, is positioned directly over a channel 50 set apart by a longitudinal partition 51 in the anchorage portion 11a of the work arm 11 for traverse by the looper threads. Centrally of its rear crosswise edge, the portion 35a of the shield 35 is formed with an upturned tab 52 to serve as an auxiliary guide for the looper threads, said guide being in line with eyes at the bottom end of a guide strip 53 extending upward to the top of the needle arm 13 of the machine frame.

From the foregoing it will be seen that I have provided a simple and efficient protective shield which can be readily attached to existing sewing machines at small expense. It is, of course, to be understood that the shield is not limited in its application to machines of the specific type herein shown by way of example, since by suitable modifications within the scope of the appended claims, it may be as readily adapted to other forms of sewing machines.

Having thus described my invention, I claim:

1. The combination in a sewing machine having a needle arm in the end of which a bar carrying a needle is confined to up and down movement, a hollow work support below and over-

reached by the needle arm, complementary stitch forming mechanism with actuating means therefor journaled within the work support; of a shield on the work support serviceable as a rest for the arm of the sewing machine operator, said shield having a configuration and area substantially like the configuration and area of the work support being secured with provision of an interspace between it and said work support for air circulation to prevent conduction thereto of heat generated incident to high speed rotation of the aforesaid actuating means.

2. The combination according to claim 1, wherein the shield is sustained by a plurality of spaced lugs of small area projecting from the work support and secured by screws whereof the shanks pass through apertures in the shield and threadedly engage into the lugs.

3. The combination according to claim 1, wherein the work support of the machine has a removable top cover, and wherein the shield is attached to said cover.

4. The combination in a sewing machine having a frame comprising a base, a hollow horizontal work arm with an anchorage portion extending at an angle to the base and a free end portion substantially at right angles to the anchorage portion, a standard rising from the base and sustaining a horizontal needle arm whereof the free end overreaches the free end of the work arm, a bar with a needle confined to up and down movement in the end of the needle arm, and complementary stitch forming mechanism at the free end of the work arm with rotary actuating mechanism therefor within the anchorage portion of the work arm; of a shield on the work support serviceable as a rest for the arm of the machine operator, said shield having a configuration and area substantially like that of the work support and being secured with provision of an interspace for circulation of air between it and the work arm to prevent conduction thereto of heat generated incident to high speed rotation of the actuating means for the complementary stitch forming means.

5. The combination according to claim 4, wherein the shield is sustained by a plurality of spaced lugs of small area projecting from the work support and secured by screws whereof the shanks pass through apertures in the shield and threadedly engage into the lugs.

6. The combination according to claim 4, wherein the end of the shield over the anchorage portion of the work arm is sustained by and secured to upstanding lugs of small area in said portion, and the other end depressed into contact with and secured to the top of the free end portion of said work arm.

7. The combination according to claim 4, wherein the work arm of the machine has a removable top cover; and wherein the shield is attached to said cover.

8. The combination according to claim 4, wherein the machine is provided with a fabric guide which is slidable longitudinally of the free end portion of the work arm; wherein the end of the shield over the anchorage portion of the work arm is sustained by and secured to upstanding lugs of small area on said portion; and wherein in the end of the shield over the free end portion of the work arm is slotted to clear the shiftable fabric guide and depressed into direct contact with the top of the last-mentioned portion of said work arm.

CHARLES F. RUBEL
